UNITED STATES PATENT OFFICE.

WILLIAM LESLIE BLACK, OF FORT MCKAVETT, TEXAS.

ANTIFRICTION DEVICE FOR SUCKER-RODS.

SPECIFICATION forming part of Letters Patent No. 712,486, dated November 4, 1902.

Application filed February 6, 1902. Serial No. 92,887. (No model.)

To all whom it may concern:

Be it known that I, WILLIAM LESLIE BLACK, a citizen of the United States, residing at Fort McKavett, county of Menard, and State of Texas, have invented certain new and useful Improvements in Antifriction Devices for Sucker-Rods; and I do hereby declare the following to be a full, clear, and exact description of the invention, such as will enable others skilled in the art to which it appertains to make and use the same.

My invention relates to antifriction devices for sucker rods or ropes or for the coupling devices thereof, and while it is particularly designed to protect the rod, rope, or coupler from wear incident to the rubbing of the moving part against the casing it likewise accomplishes the desirable result of leaving the pipe surrounding the rod practically free from obstruction, so that the flow of the liquid is substantially unimpeded, and serves to free the rollers and bearings of the antifriction device from sand and grit, whereby the durability and efficiency of the device are correspondingly increased.

My invention is illustrated in the accompanying drawings, in which—

Figure 1 represents, partly in section, a well-casing, two sucker-rod sections, and a coupler therefor, said coupler being provided with one of my improved devices. Fig. 2 is a horizontal section on line 2 2 of Fig. 1. Fig. 3 is a vertical section of a well-casing, illustrating a modified form of my device as applied directly to a rod-section. Fig. 4 is a horizontal section taken on line 4 4 of Fig. 2.

Referring to the drawings, Figs. 1 and 2, the numeral 1 represents the usual form of tubular metal casing employed in Artesian, oil, and other wells of this character, in which the sucker-rod 2 reciprocates. This rod is composed of separate sections united by couplers comprising ferrules 3 and 4, provided with the engaging screw-threaded sections 5 and 6, of the usual form well known to those skilled in the art. Between the respective members of the coupler I mount my improved antifriction device, which consists of a collar 7, provided with an internal screw-thread corresponding to the thread on the male member of the coupler. About the periphery of this ring I prefer to form vertical flanges 8, which

constitute sockets to receive the ends of the coupler-sections. Projecting radially from the periphery of the collar 7 are a series of 55 forks 9, provided with bearings at their outer ends, in which are mounted by means of suitable journal-pins or gudgeons 10 the antifriction balls or rollers 11, which engage the inner surface of the casing, and thereby maintain 60 the rod in its central vertical alinement with respect to the casing and likewise prevent the rod from rubbing against the side of the casing. By the particular arrangement of antifriction device, with its collar turned up on 65 the male member of the coupler, I avoid the possibility of dropping the device into the casing should the rods become uncoupled.

In the modification shown in Figs. 3 and 4 I provide an antifriction device which is 70 adapted to be mounted at any point on the sucker-rod. This form of my device comprises a sleeve encircling the rod, which sleeve is split longitudinally to form two mating sections 21 21, inclosing the rod between them, 75 which sections are united and firmly bound to the rod by means of suitable bolts passed through the ears 22. Projecting radially from the sleeve-sections and preferably formed integral therewith are a series of forks 23, which 80 constitute the supports for antifriction-rollers 24. The ends of these forks are provided with bearings which receive the journal-pins or gudgeons 25, upon which the antifriction-rollers 24 are mounted. These journal-pins may 85 be secured in position by nuts 26 engaging the screw-threaded ends thereof, or by cotter, as illustrated at 12 in Fig. 2, or in any other well-known manner.

It will be observed that my improved antifriction device, as illustrated in both modifications, comprises a light framework or series of forks attached to the sucker-rod which interpose a comparatively small obstruction to the flow of material in the tube, as the 95 spaces included within and between the several forks are relatively large and free.

It is obvious that the number of antifriction-rollers may be varied to suit different conditions of operation, so that each of the 100 supporting-collars is provided with two or more rollers disposed about its periphery in such relation as to preserve the alinement of the rod in the casing.

The particular form of my invention shown in Fig. 1 is designed to be applied, as indicated, to the sucker-rods at the junction-points of the various couplers. Before the 5 sections are united I screw one of my antifriction devices upon the male member of a coupler-section until it finds a firm bearing against the shoulder of said section. The mating portion of the coupler on the next 10 rod-section is then engaged with the portion of the male member which projects through the collar of my antifriction device and is screwed thereon until the collar is held firmly between the two sections. In this way my 15 antifriction device is rigidly secured to the rod, and the several antifriction-rollers are held firmly against the sides of the casing, thereby preventing the rod from leaving its central alinement or rubbing against the sides 20 of the casing.

In the form shown in Figs. 3 and 4 the device may be applied to any portion of the sucker-rod, and it will be apparent that as many of these antifriction devices may be 25 applied to the rod in such relation to each other and at such distances apart as good practice may dictate.

Having thus described my invention, what I claim is—

30 1. The combination of a sucker-rod coupling comprising two engaging members and an antifriction device comprising a collar pro-

vided with antifriction-rollers, interposed between the engaging members of the coupling.

2. An antifriction device for sucker-rod 35 couplers, comprising a collar adapted to be secured between the mating coupler members of the rod-sections, radial forks projecting from said collar and provided with bearings in their outer ends, and antifriction-rollers 40 mounted in said bearings.

3. An antifriction device for sucker-rod 45 couplers, comprising a collar adapted to be secured between the coupler members of the rod-sections and provided with an internal 50 screw-thread to engage the thread on the male coupler-section, radial forks projecting from said collar, said forks having bearings in their outer ends, and antifriction-rollers journaled in said bearings.

4. The combination with a sucker-rod coupling, of an antifriction device interposed between the mating members of the coupling and engaging with one of said members, whereby should the coupling become disassembled, the antifriction device will remain 55 in place.

In testimony whereof I affix my signature in presence of two witnesses.

WILLIAM LESLIE BLACK.
